UNITED STATES PATENT OFFICE.

WILLIAM COX, OF TORONTO, ONTARIO, CANADA.

FARE-BOX.

1,135,264.

Specification of Letters Patent. Patented Apr. 13, 1915.

Application filed June 1, 1914. Serial No. 842,293.

To all whom it may concern:

Be it known that I, WILLIAM Cox, of the city of Toronto, in the county of York and Province of Ontario, Dominion of Canada, have invented certain new and useful Improvements in Fare-Boxes; and I hereby declare that the following is a full, clear, and exact description of the same.

My invention relates to a fare box comprising an examining chamber having a cover with a fare receiving slot therein and an opening at the junction of one of the vertical sides and bottom through which the fares can pass to the magazine, the opening being controlled by two sets of intermeshing fingers, one pivoted to the bottom, and the other pivoted to said vertical side, so that they can swing into normally open relation to permit of the fares within the examining chamber passing into the magazine when the fare box is slightly tilted from its upright position and into closed relation to prevent the fares passing from the magazine into the examining chamber when the fare box is inverted, or partly so.

The invention also relates to the provision of two hinged shutters within the examining chamber arranged to swing across the fare receiving slot and close it when the fare box is inverted, so that the fares within it cannot find an exit through said slot, as hereinafter described and particularly pointed out in the claims.

In the drawings; the figure is a broken perspective view of the fare box showing the relative construction and arrangement of the parts.

Like characters of reference refer to like parts throughout the specification and drawings.

In the cover *a* of the examining chamber *b* is a slot *c* through which the fares are admitted to the examining chamber. Within the examining chamber *b*, contiguous to the cover *a* are two hinge pins *d*, *d'*, respectively, located on opposite sides of the slot *c*, and suspended from the hinge pins, *d*, *d'*, are shutters, *e*, *e'*, each of a sufficient length to swing from its hinge pin across the fare receiving slot *c*, the shutters being weighted, as shown at *f*, to accelerate their swinging movements.

At the junction of the bottom *g* with the vertical side *i* of the examining chamber *b* is an opening *h* through which the fares pass from the examining chamber into the

fare magazine, the opening *h* extending across the bottom *g* for the full width of the examining chamber *b*. Pivoted to the bottom *g* at one side of the opening *h* is a set 60 of segregated fingers *j* which normally assume an inclined position with relation to the bottom *g* so that their free ends will be slightly below the level of the bottom *g* and thus provide a normally unobstructed passage, below the lower edge of the side *i*, for the delivery of the fares from the examining chamber into the fare magazine *k*, and beneath the fingers *j* is a stop *l* to limit their downward movement when the fare box is 70 in an upright position and thus determine the size of the passage *m* existing between the fingers *j* and the bottom edge of the side *i*.

Pivoted to the side *i* is a set of segregated fingers *h'* intermeshing with the fingers *j* when the fare box is in an upright position and when inverted, and swinging clear of the fingers *j* when the fare box is 80 slightly tilted from an upright position to then provide an unobstructed passage for the fares to the fare magazine.

When the fare box is inverted, or partly so, the fingers *j* turn on their pivots until their free ends engage the side *i* and the 85 fingers *h'* turn on their pivots until their free ends engage the stop *l*, the fingers *h'* then coöoperating with the fingers *j* to close the passage from the fare magazine into the examining chamber.

By means of this construction, it is impossible for the fares delivered into the fare magazine to reënter the examining chamber. When the box is inverted, the shutters *e*, *e'* swing from their open position across the fare receiving slot and close it, so that any fares which may have been retained within the examining chamber cannot be extracted through the fare receiving slot.

Having thus fully described the nature of my invention, what I claim as new and desire to secure by Letters Patent, is:

1. In a fare box, an examining chamber, having a cover with a fare receiving slot 105 therein, through which the fares are admitted to the examining chamber, and having an opening at the junction of the bottom and one of the vertical sides through which the fares pass from the examining chamber into the fare magazine, two sets of segregated fingers, one set pivoted to the bottom 110

and supported to extend substantially horizontally across said opening, and the other set pivoted to said side to intermesh with the fingers of the first set, each set of fingers 5 moving into normally open relation with the other set, when the fare box is slightly tilted from an upright position, and moving into closed relation when the fare box is inverted.

2. In a fare box, an examining chamber, 10 having a cover with a fare receiving slot therein, through which the fares are admitted to the examining chamber, and having an opening at the junction of the bottom and one of the vertical sides through which 15 the fares pass from the examining chamber into the fare magazine, two sets of segregated fingers, one set pivoted to the bottom

and supported to extend substantially horizontally across said opening, and the other set pivoted to said side to intermesh with 20 the fingers of the first set, each set of fingers moving into normally open relation with the other set, when the fare box is slightly tilted from an upright position, and moving into closed relation when the fare box is inverted, 25 and two shutters within the examining chamber at opposite sides of the fare receiving slot and pivoted to swing across it when the examining chamber is inverted.

Toronto, May 26th, 1914.

WILLIAM COX.
